UNITED STATES PATENT OFFICE.

RENHART REIERSON, OF PORTLAND, OREGON.

DRAG-SAW MACHINE.

1,300,650.

Specification of Letters Patent. Patented Apr. 15, 1919.

Application filed March 28, 1918. Serial No. 225,218.

To all whom it may concern:

Be it known that I, RENHART REIERSON, a citizen of the United States, residing at Portland, in the county of Multnomah and 5 State of Oregon, have invented a new and useful Drag-Saw Machine, of which the following is a specification.

My invention relates to improvements in drag-saw machines used as an auxiliary to 10 gas engines or other rotary motors; and the objects of my invention are, first, to provide a mechanism which will convert rotary into reciprocating motion; second, to impart to the saw at the end of every stroke a 15 rocking motion in order to rid the cut of the sawdust which proves so troublesome in fast cutting; third, to provide an adjustable, hand-operated, self-locking clutch where- with the saw can be started and stopped 20 without interfering with the operation of the engine; should, for some reason or other, the saw become pinched during the sawing, the clutch can be adjusted to slip rather than break the machine; fourth, to 25 provide means for lifting and lowering the saw while in operation; fifth, to furnish a novel and practical means of connecting the drag-saw machine to and releasing it from the saw-log.

30 I attain these objects by the mechanism illustrated in the accompanying drawings, in which:

Figure I is a plain view of the entire machine; Fig. II, a partial side view, a section having been made across the driving shaft at line *a*—*a* in Fig. I; Fig. III, a slightly enlarged section of Fig. I taken along line *b*—*b*; Fig. IV, a side view of the clutch mechanism as it appears when detached 40 from the shaft; Fig. V, a plan view of the clutch band holder; Fig. VI, a front view of the guiding shoe for the extension bar; Fig. VII, a section through Fig. VI, taken along the line *c*—*c*; Fig. VIII, a full view 45 of the hand lever; Fig. IX, a slightly enlarged portion of the driving sprocket with special reference to its ball bearing feature; and finally Fig. X, a plan view of the clutch band tightener.

50 Similar numerals refer to similar parts throughout the several views.

On the rotary shaft 1 of a gas engine or other motor are placed in sequence cone 2, clutch band holder 3, clutch wheel 4 and 55 sprocket wheel 5. All of them are mounted loosely except clutch band holder 3 which is

keyed tightly in place by means of key 6 shown in Fig. III; the respective keyway being illustrated at 7 in Fig. IV. Set-screw 8 furnishes the safeguard against mis- 60 placement in axial direction.

The radially projecting arm 9 of the clutch band holder 3 carries a clutch band 10 which is practically a lever with the fulcrum at 11 so that cone 2, acting on end 12, can tighten the clutch band 13 attached to end 14 of said clutch band 15. To make the clutch self-locking the cone 2 is pressed, by means of hand lever 15, under end 12 until projection 16 rests on 70 the cylindrical part 17 of cone 2, causing latter to revolve in unison with the clutch until the hand lever is withdrawn again.

To permit the cone to revolve with the least possible friction the hand lever 15 is 75 provided with anti-friction rollers 18 18 (see Fig. VIII) fitting into an annular groove 19 on cone 2. For convenience's sake the hand lever 15 is shaped out of two flat iron pieces 20 20, held together by bolts or 80 rivets at 21, although any other construction may be chosen if desired. At its lower end 22 the hand lever is attached to the base plate 23 of the drag-saw machine.

For the purpose of fastening clutch band 85 13 to the clutch band tightener 10 latter extends a rod or finger 24 across the rim of the adjacent clutch wheel 4 and into the eye 25 of the clutch band 13; nut 26 prevents the eye 25 from slipping off finger 24. After 90 encircling the rim of said clutch wheel, the clutch band ends in a threaded portion 27 which enters hole 28 in lug 29 of the clutch band holder 3; nut 30 serves to adjust the clutch band to any amount of frictional grip 95 desired. Flanges 31 31 prevent a lateral escape of the clutch wheel from the encircling clutch band. It may be stated at this time that the clutch band 13 is equipped with a non-burning composition lining 32. 100

The clutch wheel hub 33, on the side nearest the sprocket wheel 5, has an enlarged bore with inside thread corresponding with the outside thread 34 on the sprocket wheel hub 35; those two elements, when screwed 105 together forming an integral part for operative purposes. The advantages of screwing them together rather than casting them in one piece are threefold; first, the sprocket wheel which is subjected to a large amount 110 of wear can easily be case-hardened; second, a ball or roller bearing 36 can conven-

iently be fitted to the hub 35 and held there laterally secure by the clutch wheel hub 33; third, the sprocket wheel 5 can, without the workman being inconvenienced by the 5 ponderous clutch wheel, be incorporated into the rack frame while the latter is being riveted together, its appearance at this stage being similar to Fig. III.

The teeth 37 of sprocket wheel 5 work in a 10 rack formed of a single, straight row of anti-friction pins 38, except at both ends 39 39 where the pins are set in a circular curve. The reasons for doing this are twofold; first, in rounding this curve a rocking motion will 15 be imparted to the saw, which shakes the sawdust from it; second, the transition from the lower race-track 40 to the upper 41 and vice versa is accomplished in a smooth and easy manner instead of making it jerky as 20 would be the case if the transition had to take place around one single end pin.

Pins 38 are riveted into an iron plate 42, the edges of which are substantially equidistant from the center line of said rack 25 pins; a metal rim 43 is secured along the edge and on this rim a railing 44 which partly forms one of the tracks 45 for the ball bearing 36 and partly covers and confines the teeth of the sprocket wheel 5 within 30 the rack frame. The complementary track 46 is riveted to the rack pins 38. The anti-friction feature of the pins 38 is illustrated in Fig. III and consists of two loosely fitting, concentric sleeves surrounding said pins.

35 To projection 49 of plate 42 is riveted the extension bar 50 and to latter again is bolted saw 51. The extension bar 50 travels between two angle iron guides 52 52, they being riveted at 53 to the base plate 23. The 40 guides in this drawing are shown curved although straight guides may be used. To insure rigidity of construction braces 54 54 are riveted at 55 to the angle iron guides 52 and at 56 to the base plate 23. A spacer bolt 45 57 connects the top of guides 52 and serves at the same time as pivotal support for the hook 58 which latter is used to engage a hook 59 in the guiding shoe 60 when the saw is to be lifted clear of the log 61; the 50 position of hook and guiding shoe in such a case are indicated in Fig. II by dotted lines 58^a and 60^a respectively.

The guiding shoe, shown in detail in Fig. VI, consists essentially of a rectangular body 55 portion with a rectangular opening 62 to permit the extension bar 50 free passage. The lateral edges 63 63 (see Fig. VII) are turned backward and inward to fit over the legs of the angle irons 52, so that shoe 60 is 60 restricted to a vertical sliding movement along the face of said angle irons. Handles 64 64 furnish a convenient means of raising or lowering the shoe and thereby the extension bar 50 with the attached saw 51.

65 A dog connects the drag-saw machine

with the log 61 and prevents latter from rolling under the reciprocating motion of the saw. This dog comprises a tube 65 whose one end 66 is pivotally connected to the base plate 23, while into the other, open 70 end 67 fits slidably a spur-carrying rod 68. The head 69 of spur 70 is bent at a right angle to said spur and high enough above the penetrating limit of the latter to permit the insertion of an ax, crowbar, or other 75 instrument under the head for the purpose of withdrawing the spur from the log. A hand-screw 71 fixes the rod 68 within the tube 65.

Brackets 71^a 71^a, bolted at 72 to the base 80 plate 23, and at 73 73 to the engine bed, keep both last named elements in proper alignment.

Having fully described my invention, it will be seen that my objects have been accomplished, and, though I have shown the preferred form of my invention, I reserve to myself the right to make minor changes in construction so long as I do not violate the disclosed principle. 90

I claim:

1. In a drag-saw machine, the combination of a rotary shaft, a sprocket wheel attached to the end of the shaft, said sprocket wheel guiding and propelling a rack frame having 95 one single row of rack pins at the longitudinal center line, said rack pins, at both ends of the row, disposed in the figure of an endless loop, adapted to impart a rocking motion to the saw at the end of every stroke; 100 an extension bar secured to one end of the rack frame and a saw removably connected to the end of the extension bar.

2. In a drag-saw machine, the combination of a rotary shaft, a sprocket wheel 105 having on one side a protruding hub and being attached to the end of the shaft, a rack frame guided and propelled by said sprocket wheel and composed of an elongated body portion having one single row of rack pins 110 at the longitudinal center line of the body portion, said pins, at both ends of the row, disposed in the figure of an endless loop, adapted to impart a rocking motion to the saw at the end of every stroke, the edge of 115 the body portion having a railing confining the sprocket wheel within the rack frame and serving as track for the hub of the sprocket wheel, the complementary track being attached to the rack pins; an extension 120 bar at one end of the rack frame and a saw at the end of the extension bar.

3. In a drag-saw machine, a horizontal base plate having brackets on one side for securing the base plate to an engine bed, 125 having, on the side nearest to the engine, means for attaching a clutch shifting lever, having, at the end nearest to the log, two substantially vertical angle iron posts, and braces extending from the top of the posts 130

to the base plate, said posts being connected at the top and having depending therefrom a swinging catch, a shoe slidably mounted on the angle iron posts, having a rectangular perforation through the body to permit free passage to the extension bar of a saw, having handles extending laterally and outwardly from the shoe to permit the lifting or lowering of the saw during operation, and having means of engaging said swinging catch; the base plate having at the end nearest to the log means for attaching a dog to maintain engine, base plate and log in a fixed relation.

RENHART REIERSON.
